R. S. BAKKEKILDE
RADIATOR CONSTRUCTION

1,828,637

Filed Aug. 3, 1929

UNITED STATES PATENT OFFICE

ROBERT SCHÖNFIELDT BAKKEKILDE, OF ODENSE, FYEN, DENMARK

RADIATOR CONSTRUCTION

Application filed August 3, 1929, Serial No. 383,411, and in Denmark August 3, 1928.

The present invention relates to a base and top member for radiators for central heating plants.

The distinguishing feature of the invention is that the radiator rests on a base consisting of a pair of side pieces which may be connected to a front piece, while similarly a pair of corresponding side pieces, and between these a front piece, are disposed on top of the radiator, there being provided on top of these side pieces a cover plate, for instance of marble.

By this invention the advantage is attained that a chamber is formed above and below the radiators in which chambers the supply and discharge pipes with the valves belonging thereto may be hidden, so that all the pipes joined to a radiator will be perfectly invisible, whereby the appearance of the radiator will be improved.

The loose base and top members may be arranged in such a manner that they may be used for radiators of different dimensions, and they are extremely easy to assemble and to take apart again without any tools.

At times it may be of importance to be able to dispose the said supply and discharge pipes vertically along the sides of the radiator, without the said pipes thereby becoming visible, and it may also be a drawback that the total height of the radiator concerned is determined by the height of the radiator units and, consequently, for instance when the radiator is to be erected in a window recess, cannot be adjusted to suit the level of the window sill.

Another object of the invention is therefore to connect the base and top members by means of intermediate members which may be adjustable in vertical direction, so that the upper cover plate of the radiator may be adjusted to suit the level of the window sill, ducts for pipe lines and the like being at the same time formed inside of the intermediate members.

The invention is shown on the drawings, where

Fig. 1 shows a radiator in front elevation

Fig. 2 shows one of the base members in top-view

Fig. 3 shows one of the top members in top view

Fig. 4 shows the radiator in side elevation

Fig. 5 shows another radiator in front elevation

Fig. 6 shows a section along the line VI—VI in Fig. 5

Fig. 7 shows a section along the line VII—VII in Fig. 5

On the drawings 1 is a radiator of suitable shape and size composed of units. The radiator rests on two base members 2, one side of which may be fitted with an extension 3 as shown on the drawings. The side pieces of the base members are fitted with lugs 4, 4' 65 with a hole for a bolt 5 serving as pivot for a swing cover 6.

For smaller radiators the base members 2 are used in such a manner that the extensions 3 turn towards the rear, and the cover 6 70 may then be pivoted about a bolt between the lugs 4, and in the case of a wider radiator the side pieces are turned in such a manner that the extensions 3 face towards the front, and the cover 6 is then pivoted about the bolt 5 75 between the lugs 4'.

The top members are arranged in the same manner and consist of two pieces 7, one side of which is fitted with extensions 8. Here too a bolt 5 is provided between the side 80 pieces, and the bolt serves as pivot for a swing cover 6'. Hereby a space closed at front and on the sides is formed above and below the radiator in which space the supply and discharge pipes 9, 10 with the adjusting 85 valve 11 may be hidden in such a manner that the appearance of the radiator will be improved.

The adjusting valve may easily be manipulated when the cover 6' is swung up.

The device may otherwise be varied in different ways, without the principle underlying the invention being deviated from. There may for instance be provided loose extension pieces 3 to be connected to the fixed 95 extensions when very wide radiators are used, and above the pieces 7 there may be provided a cover plate 12.

The base and top members may similarly be held together by means of bolts running 100

therethrough, and the covers 6, 6' do not have to be in one piece, but may be composed of a series of juxtaposed flaps.

In the construction shown in Figs. 5-7 1 indicates the radiator units resting at both 6 ends on base members 2. In these base members intermediate members 13 are inserted and at the top the intermediate members support the top members 7. In the same manner as in Figs. 1 to 4 the top as well as the 10 base members are interconnected by means of bolts 5 with flaps 6 and 6'.

At the sides the intermediate members 13 may be closed by plates 14 of suitable material, in such a manner that cavities 15 for pipes, fittings and the like are formed. As mentioned above, the intermediate members 13 may slide in the base member 2 and the top member 7 and the top member can be 20 held securely at any desired level by means of devices such as screws or the like not shown on the drawings.

Having now described my invention, what I claim as new and desire to secure by Letters 25 Patent is:—

1. In combination, a radiator including pipe connections and regulating means for the supply and discharge of heating liquid, and a base and a top, said radiator resting 30 on the base and supporting the top thereon, said base and top being hollow and forming chambers accommodating and concealing the pipe connections and regulating means, said base and top each including a plurality of 35 parts and a movable front member connecting said parts, each part being of unequal dimensions at the front and back permitting reversal thereof to accommodate the base and top to radiators of varying sizes.

40 2. In combination, a radiator including pipe connections and regulating means for the supply and discharge of heating liquid, and a base and a top, said radiator resting on the base and supporting the top thereon, said base and top being hollow and forming 45 chambers accommodating and concealing the pipe connections and regulating means, said base and top each including a plurality of parts and a movable front member connecting 50 said parts, and a connecting bolt for the parts of the base and top, respectively.

55 3. In combination, a radiator including pipe connections and regulating means for the supply and discharge of heating liquid, and a base and a top, said radiator resting on the base and supporting the top thereon, said base and top being hollow and forming 60 chambers accommodating and concealing the pipe connections and regulating means, said base and top each including a plurality of parts and a movable front member connecting 65 said parts, and hollow intermediate members connecting the superposed parts of the base and top and being of hollow form.

66 4. In combination, a radiator including

70 pipe connections and regulating means for the supply and discharge of heating liquid, and a base and a top, said radiator resting on the base and supporting the top thereon, said base and top being hollow and forming 75 chambers accommodating and concealing the pipe connections and regulating means, said base and top each including a plurality of parts and a movable front member connecting 80 said parts, and hollow intermediate members connecting the superposed parts of the base and top and being of hollow form, each intermediate member and the parts of the top and base associated therewith forming an extensible unit permitting its application to radiators of varying height.

85 In testimony whereof I affix my signature.
ROBERT SCHÖNFELDT BAKKEKILDE.
